UNITED STATES PATENT OFFICE.

AUGUSTIN LEON JEAN QUENEAU, OF PHILADELPHIA, PENNSYLVANIA, ASSIGNOR TO WETHERILL FINISHED CASTINGS COMPANY, OF PHILADELPHIA, PENNSYLVANIA, A CORPORATION OF PENNSYLVANIA.

CASTING OF METALS.

1,043,867.

Specification of Letters Patent.

Patented Nov. 12, 1912.

Application filed October 12, 1909. Serial No. 522,274.

To all whom it may concern:

Be it known that I, AUGUSTIN LEON JEAN QUENEAU, a citizen of the Republic of France, residing in the city and county of Philadelphia and State of Pennsylvania, have invented certain new and useful Improvements in Casting of Metals; and I do hereby declare the following to be a full, clear, and exact description of the invention, such as will enable others skilled in the art to which it appertains to make and use the same.

This invention relates to the reproduction, in metal and by a casting operation, of metal articles generally, the metal article serving as a pattern for making metal casting dies in which the casting is effected.

It is characteristic of the invention that it permits the reproduction of the metal article to be duplicated, with absolute accuracy and minuteness of detail, without requiring the services of a pattern maker, and, if desired, not only in the same metal of which the original article is made, but also in metal casting dies of the same metal, so that both in the operation of forming the metal casting dies and in the operation of casting the finished reproductions therein, the same rate of expansion and contraction will prevail throughout.

For purposes of illustration, I have shown the invention as applied to the reproduction of small castings and particularly to the reproduction of miter gears, but it will be apparent that the invention has varied and wide applications as regards the character of the article to be reproduced and that it is not limited, therefore, to the reproduction of any particular size or kind of metal article.

I have also shown the invention as adapted to be used in a casting operation wherein the metal is raised into the mold cavity from below upwardly, as, for instance, in pneumatic casting, but broadly considered it will, of course, be understood that it is not limited to this particular manner of supplying the mold cavity with the casting metal.

In the accompanying drawings, Figure 1 represents, partly in vertical section and partly in elevation, suitable apparatus for the practice of my invention and illustrates particularly the initial step of casting one of the metal casting dies for the reproduc-

tion of the miter gear shown in said figure and shown on a larger scale in Figs. 9 and 55 10. Fig. 2 represents, in vertical section, a detached view of the head-plate forming a part of the apparatus shown in Fig. 1. Fig. 3 represents, in vertical section, the casting made in the said initial stage of the operation with the miter gear embedded therein. Fig. 4 represents, in vertical section, the same parts shown in Fig. 3 but with certain alterations which adapt it to use in the next succeeding stage or step of the process. Fig. 65 5 represents, partly in vertical section and partly in elevation, the same apparatus shown in Fig. 1 but with the employment, as the head-plate of the mold, of the block and its associated miter gear shown in Fig. 4. 70 Fig. 6 represents, in vertical section, the casting produced in the step or stage of the process indicated in Fig. 5. Fig. 7 represents a like view to Fig. 6, but with the casting somewhat modified to permit it to communicate with the gate of the mold. Fig. 8 represents a view similar to Figs. 1 and 2, showing the final step or stage of the process, wherein the castings made in the operation shown in Figs. 1 and 5 and constituting 80 the metal casting dies are employed to produce the final reproduction. Figs. 9 and 10 represent, on a larger scale than the preceding figures, the miter gear chosen as an illustration of the method of casting involved in 85 the practice of my invention.

Similar letters of reference indicate similar parts throughout the several views.

Referring to the drawings, 11 indicates the base-plate of the main mold by means 90 of which the two sections or casting dies of the article mold are to be formed. This base-plate may conveniently be provided with a screw-threaded projection 40, whereby it may be conveniently attached to a corresponding screw-threaded projection of any suitable pneumatic casting apparatus of well-known type, in such manner that the gate 12 of the mold shall be in air tight contact and alinement with the casting nozzle 100 or dip pipe of the pneumatic casting apparatus. The gate 12 is preferably of tapering form and leads into a chamber 13 created by a cavity in a metal block 14, secured in any suitable manner to the base-plate 11. 105 At its upper portion, the block 14 is pro-

vided with an annular shoulder 15, in which is seated a head-plate 16. Both the block 14, which forms the side walls of the mold, and the head-plate 16 which forms the cover, 5 are preferably made of cast iron.

The head-plate has a central bore, as indicated at 17 in Fig. 2, to receive a spindle 18 that is supported from the top of the head-plate by means of a collar 19 into which a 10 cross-pin 20, carried by the upper part of the spindle is fitted. The collar 19 rests upon the upper surface of the head-plate and supports the spindle 18 whose lower end 21 projects within the mold cavity 13. 15 The head-plate is further provided with the countersunk recesses 22, 23 (see Fig. 2), in order to receive and seat the miter gear, as shown in Fig. 1, said miter gear fitting snugly upon the projection 21, so as to be 20 sustained in place. When the miter gear pattern is in the position indicated, it is partly contained within the head plate and partly extends into the mold, and the projection 21 extends still farther into the mold 25 cavity 13.

When the parts are in the position shown in Fig. 1, the apparatus is ready for the molding of one of the mold sections or metal casting dies. The molten metal from which 30 the casting die is to be formed is thereupon raised into the mold through the gate 12 until the mold cavity or chamber 13 is filled. The upward movement of the entering metal is resisted, during this filling 35 operation, and the head-plate is held on its seat in the block 14, by means of a locking device 26 that preferably takes the form of a plate adapted to be slid laterally into notches 27 made in the upright post 28, 40 and this locking plate is provided centrally with a screw-threaded aperture within which fits a corresponding screw-threaded pressure pin 41 having an actuating lever 42, as shown. The pressure pin 41 is located directly above the collar 19 and spindle 18, 45 and firmly holds the head-plate, the collar and the spindle against vertical movement while the mold cavity 13 is filling. When the molten mass has set, the pressure of the 50 screw-threaded pin 41 upon the spindle 18 is released and the locking plate and head-plate are removed, which will leave the miter gear adhering to the molded block 29, in the manner shown in Fig. 3. The 55 block is then taken out of the mold and the sprue 30 is cut off, after which the block is rabbeted at its upper part, as shown at 31 in Fig. 4. The lower part of the block is then bored out, as shown at 32 to form a 60 continuation of the recess that had been formed in the block by the projection 21 of the spindle 18.

When the block 29, carrying the miter gear, has been treated in the manner indicated in Fig. 4, it is ready to serve as a

head-plate in the next succeeding operation of forming the second casting die or mold section for the article to be reproduced. This second casting die or mold section is cast, like the first casting die or mold section, in the cavity 13, but, as illustrated in Fig. 5, there is substituted for the head-plate 16, the casting die 29. In order to support the casting die 29, which is of slightly less diameter than the mold cavity, 70 a strip 33 is inserted, which rests upon the shoulder 15 of the mold wall 14, in such way as to engage the rabbet 31 of the block 29, as shown in Fig. 5. The spindle 18 is then passed downward through the block 29 75 and through the hollow interior of the miter gear, and is again supported by means of its cross-pin 20 from the collar 19 which, in this case, rests on top of the block 29. The locking plate 26 is then placed in position as before, and the screw-threaded pin 41 is caused to bear against the spindle 18, so as to resist the upward pressure of the molten metal when the latter is introduced into the mold cavity. 80

It will be apparent that when the parts are arranged as shown in Fig. 5, the resulting mold block will have the form shown in Fig. 6, *i. e.*, the metal will flow over and cover the surfaces of the miter gear employed as the pattern and that are still left uncovered and will conform to the lower surface of the molded block 29 and its adjacent parts. The second molded block, which is indicated in Fig. 6 by the numeral 95 34 is thereupon bored out at 35, after it has been taken out of the mold and then has the appearance shown in Fig. 7.

The result of the operations described is the formation of the two molded blocks or metal casting dies 29, 34 which have therein the intaglio impression of the miter gear employed as the pattern. When the blocks are placed together, the cavity formed between them will conform exactly in size and shape to the contour of the pattern and will represent it with absolute accuracy and minuteness of detail. In order to use these metal casting die sections for the reproduction of copies of the original miter gear employed as a pattern, the said casting die sections are used in the original apparatus in the manner indicated in Fig. 8, the casting die section 34 that was molded last being placed within the mold cavity 13 in 105 such manner that the bore or passage 35 will register with the gate 12. The block 29 that was first molded, and from which the miter gear employed as a pattern has been removed, is then placed in an inverted position over the block 34, after which the spindle 18 is passed downward into the relatively small cavity that exists between the casting die sections 29 and 34, said spindle being supported by the pin 20 as before. 110 115 120 125 130

- The locking plate 26 is then placed in position and the screw pin 41 is turned so as to hold the two casting die sections together during the entrance of the molten metal, which latter is forced upwardly into the small mold cavity through the gate 12. The metal entirely fills this cavity and flows into the indentations formed in the die casting sections by the gear teeth of the pattern.
- 10 Where the object to be reproduced is a miter gear, as shown, the molten metal will surround the end portion 21 of the spindle 18 in such manner as to form the hollow hub for the reproduced miter gear.
- 15 When the metal has set, the locking plate and the block 29 are removed, after which the molded gear is taken out of the block 34. It will be found that the blocks or casting die sections separate readily from each other and from the molded object, and, where the casting die sections are made of the same metal as the object to be molded, the several members of the assemblage contract and expand at the same rate thereby correspondingly lessening any liability to cracking and checking.

After the molded miter gear or other metallic object has been removed from the mold, the sprue 36 (Fig. 8), together with the solid part carried by the hub and molded in the passage or bore 35 of the block 34, are cut off, whereby the reproduction will have the configuration of the original miter gear shown in Figs. 9 and 10. The gear as thus reproduced will have a bore or passage 37 extending completely through the same, owing to the fact that the solid part of the mass has been cut away as above explained. This hollow interior of the gear is formed by the casting of the metal about the continuation 21 of the spindle 18, as will be understood.

When the die casting sections 29, 34, have been once produced, they are available for producing any number of copies of the original miter gear or other metal pattern, by assembling them in the position indicated in Fig. 8, and casting therein as hereinbefore described. The die casting sections 29 and 34 require absolutely no cutting or machining at their molding surfaces, and can therefore be produced very cheaply and quickly in the manner described and with the assurance that they will accurately reproduce the exact configuration of the original article.

In the drawings, for simplicity of illustration, I have shown the employment of but a single unit as the pattern article from which the casting dies are produced; but it will be evident that the housing 14 may, if desired, receive any suitable number of pattern articles similarly located therein on like supporting spindles, whereby from such multiple units the casting dies produced will

have a corresponding capacity of reproduction.

Having thus described my invention, what I claim is:—

1. The method of reproducing metal articles by casting, which consists in making sectional die castings in intaglio of the article, employing the article to be reproduced as a pattern, removing the pattern article, assembling the sections and casting the reproduced article therein; substantially as described. 70

2. The method of reproducing metal articles by casting, which consists in making sectional die castings in intaglio of the same metal of which the article to be reproduced is composed, employing the article to be reproduced as a pattern, removing the pattern article, assembling the sections and casting the reproduced article therein; substantially as described. 80

3. The method of manufacturing metal mold sections for the reproduction of metal articles by casting, which consists in casting molten metal in a suitable mold about a portion of the article to be reproduced so as to embed such portion in the cast block, removing the block from the mold with the pattern partially embedded therein, and using said block in connection with the mold to cast a second block of metal about the exposed portion of the pattern article; substantially as described. 90

4. The method of manufacturing metal molds for the reproduction of metal articles by casting, which consists in supporting the metal article to be reproduced from the head plate of a suitable mold in such manner that it will project partially into the mold cavity, admitting molten metal into the mold cavity to form a cast block therein in which the pattern article is partially embedded, removing said block from the mold with the pattern article so embedded, boring out the center of the block, supporting the block in inverted position as a head plate for the mold, with a spindle extending into the bore therein and into pattern article, then casting molten metal about that portion of the pattern article which remains exposed, and finally boring the second block to form a passage therein communicating with the gate of the mold; substantially as described. 100

5. In apparatus for manufacturing metal molds, for the reproduction of metal articles, a mold having a base plate provided with a gate, a head plate, and means to support the pattern article from the head plate so that it projects into the mold cavity; substantially as described. 110

6. In apparatus for manufacturing metal molds, for the reproduction of metal articles, a mold, a head plate for the mold having a cut away portion in which the pattern article is partially received, and means to 120

support the pattern article from said head plate while seated in the cut-away portion; substantially as described.

7. In apparatus for manufacturing metal molds for the reproduction of metal articles the combination with a mold having an inlet gate for molten metal, of a head plate or cover, and a spindle extending through the head plate or cover into the mold and arranged to support the pattern article in the mold cavity; substantially as described.

8. In apparatus for manufacturing metal molds for the reproduction of metal articles, the combination with a mold, of a head plate, a spindle passing through the head plate into the mold and provided with means to support the pattern article within the latter, a collar fixed to the spindle exteriorly of the mold and resting on the head plate, and

a locking device above the collar to resist upward movement of the head plate and spindle; substantially as described.

9. In apparatus for manufacturing metal molds for the reproduction of metal articles, the combination with a mold, of a head plate having a recess in its under surface to receive the pattern article, and a spindle passing through the head plate and arranged to support the pattern article within said recess, said spindle having a continuation upon which the pattern article fits; substantially as described.

In testimony whereof I affix my signature, in presence of two witnesses.

AUGUSTIN LEON JEAN QUENEAU.

Correction in Letters Patent No. 1,043,867.

It is hereby certified that in Letters Patent No. 1,043,867, granted November 12, 1912, upon the application of Augustin Leon Jean Queneau, of Philadelphia, Pennsylvania, for an improvement in "Casting of Metals," an error appears in the printed specification requiring correction as follows: Page 3, line 75, strike out the article and syllables "the repro-"; and that the said Letters Patent should be read with this correction therein that the same may conform to the record of the case in the Patent Office.

Signed and sealed this 10th day of December, A. D., 1912.

[SEAL.]

C. C. BILLINGS,
Acting Commissioner of Patents.

support the pattern article from said head plate while seated in the cut-away portion; substantially as described.

7. In apparatus for manufacturing metal molds for the reproduction of metal articles the combination with a mold having an inlet gate for molten metal, of a head plate or cover, and a spindle extending through the head plate or cover into the mold and arranged to support the pattern article in the mold cavity; substantially as described.

8. In apparatus for manufacturing metal molds for the reproduction of metal articles, the combination with a mold, of a head plate, a spindle passing through the head plate into the mold and provided with means to support the pattern article within the latter, a collar fixed to the spindle exteriorly of the mold and resting on the head plate, and

a locking device above the collar to resist upward movement of the head plate and spindle; substantially as described.

9. In apparatus for manufacturing metal molds for the reproduction of metal articles, the combination with a mold, of a head plate having a recess in its under surface to receive the pattern article, and a spindle passing through the head plate and arranged to support the pattern article within said recess, said spindle having a continuation upon which the pattern article fits; substantially as described.

In testimony whereof I affix my signature, in presence of two witnesses.
